UNITED STATES PATENT OFFICE.

GUIDO FORNACA, OF TURIN, ITALY.

TWO-CYCLE COMBUSTION-ENGINE.

1,176,951.

Specification of Letters Patent. Patented Mar. 28, 1916.

Application filed March 17, 1914. Serial No. 825,222.

To all whom it may concern:

Be it known that I, GUIDO FORNACA, a subject of the King of Italy, residing at Turin, in the Province of Piedmont, Italy, 5 have invented certain new and useful Improvements in Two-Cycle Combustion-Engines, of which the following is a full, clear, and exact specification.

This invention relates to two-cycle combustion engines, and has particular reference 10 to engines of the type wherein the burned gases are forced out through the exhaust port by a blast of compressed air, a portion of which air is retained in the cylinder and 15 mixed with the next fuel charge.

The object of the invention is to provide a controlling means for the blast by which the blast will not be admitted to the cylinder until after the working piston has opened 20 the exhaust port, and permitting the admission of air even after the working piston closes the exhaust port on the return stroke.

The further object of the invention is to locate the blast controlling mechanism at the 25 outer or lower end of the cylinder, so that it will be protected from excessive heat and pressure, and thereby rendered capable of being more simply constructed and operated.

The invention is especially applicable to 30 the Diesel type of two-cycle engine, wherein the fuel is injected into air compressed in the cylinder, forming a charge which is ignited by the heat of compression. In the embodiment of the invention shown herein, the 35 outer end of the cylinder is provided with an exhaust port or ports on one side which are opened just before the piston reaches the outer end of its working stroke, and opposite to the exhaust ports are placed blast inlet ports, which are uncovered by the piston before it uncovers the exhaust ports, and covered by the piston after it covers the exhaust ports. For controlling the blast, an external 40 mechanically driven valve is provided, which 45 in coöperation with the stationary ports only admits the blast after the exhaust ports have opened and partially exhausted the gases, and continues the admission of air even after the exhaust ports have closed, thereby securing 50 an economy by permitting the burned gases to naturally exhaust down to atmospheric pressure and also enabling a sufficient duration of blast inlet to fully charge the cylinder with fresh air.

55 In the accompanying drawings, Figure 1 is a vertical section of a cylinder embody-

ing the invention; Fig. 2 is a horizontal section, and Figs. 3, 4 and 5 are diagrams showing a preferred timing of the various parts.

1 represents a cylinder having a working piston 2, exhaust ports 3, blast inlet ports 4, a blast supply pipe 5 and a rotary blast controlling valve 6. The fuel may be admitted at the top of the cylinder through suitable valves disposed in the hole 7. The piston 2 60 may be provided with a curved head as 8, or other suitable formation to properly direct the air blast so as to fully fill the entire cylinder and expel the burned gases through ports 3.

Referring to Figs. 3, 4 and 5, Fig. 3 shows the piston after the exhaust of burned gases through ports 3 has commenced, but the air blast is still cut off by valve 6, even though the inner blast ports 4 were uncovered by the piston 2 before it uncovered exhaust ports 3. Up to this time, the gases in the cylinder exhaust practically down to atmospheric pressure without any external air pressure. In Fig. 4, the piston 2 is almost 70 at its outer dead center, with maximum opening of the exhaust ports 3, and the valve 6 opening to permit the air to enter through ports 4. It will be observed that the air ports flare toward the cylinder head 75 and the first air admitted strikes the upper corner of the piston and is deflected upwardly, as shown by the arrow in Fig. 4, thereby causing the exhaust gases to pass out through port 3 as shown by the exhaust 80 port arrow in Fig. 4.

In Fig. 5, the piston 2 has moved upwardly on the return stroke and closes the exhaust ports 3, but air is still being admitted to the cylinder through the valve 6 85 and the ports 4. The advantage of this is that the pressure in the cylinder can become equal to that of the scavenging reservoir, which in effect corresponds to an increase in the volume of air which will be 90 compressed by the piston. This in turn permits of burning a greater quantity of fuel, and therefore increases the efficiency 95 of the engine.

The distributing valve 6 in combination 100 with the wide blast ports 4 is thus located so as to be away from the excessive heat at the head of the cylinder, and can be easily driven and lubricated, because it is only subject to the air pressure and not to hot gases. 105 It may be driven from the main engine shaft at the same speed, and suitably timed, and 110

of course with a multiple cylinder engine these distributing valves 6 will control each cylinder in proper sequence.

The invention is readily applicable to reversing engines, to accomplish which it is simply necessary to alter the relative position of the distributing valve 6 to the engine shaft, as by turning the shaft of the valve 6 through a certain angle while the main 10 shaft is stationary. Means for doing this, such as lost motion connections or spaced driving lugs, are well known and are unnecessary to a full understanding of this invention.

Having thus described my invention, I declare that what I claim as new and desire to secure by Letters Patent, is:—

1. The combination with a cylinder having blast and exhaust ports, and a piston 20 controlling said ports, of a valve controlling the entire blast, opening after said piston has uncovered both of said ports, and cutting off the blast after the piston has closed said exhaust.
2. The combination with a cylinder having a blast inlet port and an exhaust port adjacent its outer end, and a piston, of blast controlling means for admitting the initial blast a predetermined time after said piston opens said exhaust port, and cutting off said blast a predetermined time after the piston closes the exhaust port.
3. The combination with a cylinder having blast and exhaust ports at its lower end,

of a mechanically driven valve for delaying the entire blast a predetermined time after the exhaust is opened by the piston and continuing the blast a predetermined time after the exhaust is closed by the piston to charge the cylinder with air at the blast pressure. 35 40

4. The combination with a cylinder having elongated inwardly flared blast inlet ports at its lower end, of a convex piston, exhaust ports shorter than said blast ports and passed by the piston later in the outward stroke, both ports being open at the outer end of the stroke, and means for admitting the initial blast against the top of the piston on its outward travel after said exhaust port has been opened and cooperating with said flared port to direct the blast upwardly toward the head of the cylinder. 45 50

5. In a two-cycle engine, a cylinder having an exhaust port and an elongated blast port; a rotary valve controlling said elongated blast port and rotating therein in such a direction as to direct the blast first on the head of the piston, then upwardly toward the cylinder head as the piston travels on its compression stroke. 55 60

In testimony whereof I affix my signature, in presence of two witnesses.

GUIDO FORNACA.
